MACHINE FOR WASHING DISHES
AND THE LIKE

Joseph M. Drees, Saratoga, Calif.

Application March 26, 1949, Serial No. 83,596

15 Claims. (Cl. 134—185)

1

This invention relates to an improved machine for washing dishes and the like. The object of this invention is primarily an impeller designed to give a more concentrated and better directed washing stream with a minimum power input and with a minimum of impeller vibration transmitted to the case.

Another object is to achieve a uniform return of water striking the top of the case so as to flush the outside bottom of such items as cups and glasses being cleaned.

A further object is to remove food particles and greases from the washing fluid without the danger of plugging the domestic plumbing system.

Additional objects are to provide means of more effectively rinsing articles so washed, and to flush the case clean.

The features of my invention for carrying out the above objects and advantages include: a rotating impeller the bucket blades of which pick up liquid and eject the liquid in various directions by action of centrifugal force; means to impart axial reciprocating movement to the rotating impeller; means to control the liquid level at said impeller suitably for the bucket blades; easily removable combination drainage device and trap; and a manipulable rinsing device which can be moved longitudinally during rinsing.

I am aware that some changes may be made in the general arrangements and combinations of the several devices and parts, as well as in the details of the construction thereof without departing from the scope of the present invention as set forth in the following specification, and as defined in the following claims; hence I do not limit my invention to the exact arrangements and combinations of the said device and parts as described in the said specification, nor do I confine myself to the exact details of the construction of the said parts as illustrated in the accompanying drawings.

With the foregoing and other objects in view, which will be made manifest in the following detailed description, reference is had to the accompanying drawings for the illustrative embodiment of the invention, wherein:

Fig. 1 shows the front elevation of the machine.

Fig. 2 is a side elevation of the machine.

Fig. 3 is a front elevation partly in section to show construction of the rinsing, waste segregation and draining mechanism.

Fig. 4 is a side section through about the center of the machine to show further the rinsing, waste segregation and draining mechanism, and also the impeller hub and blade channels.

2

Fig. 5 is a top sectional view without rinsing mechanism baffles or racks, showing the impeller and the manner in which it is mounted, also showing a top view of the drain.

Fig. 6 is a fragmental sectional view of the journal mounting of the impeller.

Fig. 7 is a side view of the impeller at one end of its stroke of movement.

Fig. 8 is an end view of the impeller in the position of Fig. 7.

Fig. 9 is a fragmental sectional view of the impeller frame.

Fig. 10 is a side view of the impeller in an intermediate position during its axial movement from said first position.

Fig. 11 is an end view of the impeller in the position of Fig. 10.

Fig. 12 is a side view of the propeller at the other end of its stroke.

Fig. 13 is an end view of the impeller in said other end position of Fig. 12.

Fig. 14 is a cross sectional view of the middle of the impeller hub.

Fig. 15 is a side view of the impeller in an intermediate position during its travel from said second end position toward said first end position.

Fig. 16 is an end view of the impeller in said second intermediate position.

Fig. 17 is a sectional side view of an alternate cam drive.

Fig. 18 is an end view of the alternate type impeller shaft and cam drive.

Fig. 19 is a longitudinal view of the alternate type impeller together with follower and follower bearing, and

Fig. 20 is an end view of Fig. 19.

In this illustrative embodiment an impeller 1 is rotated by and is reciprocable on an impeller shaft 2, which latter is suitably mounted in a casing 3 and is driven by a suitable drive mechanism 4. The impeller 1 is supported above a trough 6 which contains the liquid used in washing or spraying. The liquid level 7 is maintained by a suitable level control so that bucket blades 8 protruding from the impeller periphery dip into the liquid for picking up a quantity of the liquid and spraying it outwardly by action of centrifugal force created by the rotation of the impeller.

This device may be used in various combinations for various purposes of spraying or washing, although it is herein illustrated as in a dish-washing machine.

In detail, the impeller 1 broadly includes a hub 9 journaled on the impeller shaft 2, the circumferentially spaced bucket blades 8 on the hub 9,

and a device to impart an axial component force to the impeller to shift it axially back and forth on the impeller shaft 2. In the form shown in Figs. 7 to 16 inclusive, a pair of spaced hubs 9 are mounted on the opposite ends of barrel or cylindrical cam frame 11. A cam path 12 is cut in the hollow cylindrical frame 11. This cam path 12 is an endless reversing path, namely it first extends spirally and longitudinally around one half of the cylindrical frame 11 and then it 5 rounds around at the end of the frame 11 into a reversing loop 13, and then spirally and oppositely around the other half of the frame 11 to the other end and the other reversing loop 13 back to the first half of the spiral path. Thus the 10 cam path 12 extends spirally and longitudinally around the entire cylindrical frame 11 in opposite directions on the opposite longitudinal halves of said frame and continuously around at each 15 end of the frame 11.

The frame 11 is, in effect, split spirally and longitudinally in two halves by the groove of the cam path 12. A sleeve 14 around the middle portion of the frame 11 holds the frame halves or sections together. This sleeve 14 has diametrically opposite outwardly projecting pockets 15 along the portions thereof which overlap the cam path 12 so as to accommodate the outer end of a cam follower 17 therethrough.

This cam follower 17 includes a follower hub 18 fixed on the shaft 2, a follower stem 19 extended radially from the hub 18, a follower head or roller 21 rotatably held on the outer end of the stem 19, and a spacer bushing 22 on the stem 19 between the roller 21 and the hub 18. A balancing stem 23 extends radially oppositely to the follower stem 19, and it has a counterweight 24 thereon to maintain a balanced rotation and obviate whipping or extreme vibration of the shaft 2. The follower roller 21 rides in the cam path 12 to impart rotation to the impeller 1. The force thus exerted on the cam path has a substantial component parallel with the axis of the impeller frame 11 and in opposite direction in the opposite spirals of the cam path 12, which component causes the endless reversing cam path to ride on the follower roller 21 as the impeller 1 is rotated and thus reciprocates the impeller 1 on the shaft 2 simultaneously with its rotation.

In the form of the impeller heretofore described, there are two bucket blades 8 in diametrically opposite positions on each impeller hub 9. These bucket blades 8 protrude generally tangentially outwardly from the periphery of the hub 9. Each bucket blade 8 is formed of a pair of opposed sides 26, connected at their outer edges by a bucket heel or bottom 27 which converges to the hub periphery. The outer edges of the bucket sides 26 are correspondingly inclined. The projecting leading edge 28 of the bucket bottom 27 is slightly curved toward the hub periphery to facilitate the picking up of water during rotation. In the bucket bottom 27 is formed a blade channel or ejector channel 29, which extends from about the inner end corner 31 of the bucket bottom 27 outwardly and on the outside of said bottom 27. The bottom 27 has a slot 32 therethrough along the channel 29 so that water flows from the bucket into the channel 29. The outer end 33 of the channel is open and operates as the spray orifice. When the impeller is rotated the leading edge 28 of the bucket blade 8 picks up water from the trough 6. Because of the inertia the water is trapped in the bucket corner 31. The action of centrifugal force then causes

the trapped water to flow to the most radial part of the bottom and along the channel 29 and fly free from the outer end or channel orifice 33. This channel orifice 33 is spaced inwardly from the bucket leading edge 28. This action through the channel produces a discharge or ejection of liquid in comparatively large drops, thus reducing the atmospheric resistance per unit mass discharged. The drops so discharged strike the articles to be cleaned at a comparatively greater velocity.

Each channel 29 is pitched in a selected axial or transverse incline with respect to the bucket bottom 27. For instance in the opposite blades 8 on a unit the channels 29 are pitched oppositely to one another so as to give to the respective discharge streams opposite components in axial direction. This action, especially when combined with the reciprocation of the impeller, serves to direct the liquid at an angle to both sides of a plane normal to the impeller shaft, and in dish-washing practice, thus wash both sides of dishes suitably held in place.

As illustrated in Figs. 7, 10, 12 and 15 the axial component of rotating force between the cam follower and the cam path moves the impeller from the extreme position of Fig. 7 through the middle position of Fig. 10 to the other extreme position of Fig. 12, and then reversing through the end loop of the cam path, back through the return middle position of Fig. 15 to the initial position of Fig. 7. The respective corresponding bucket blade positions are shown in Figs. 8, 11, 13 and 16 showing the ejection of water drops in the various directions. As the axial components of rotating forces on the impeller on the opposite sides of the cam path are opposite, the impeller reverses its axial motion every time the follower transfers from one side of the path to the other.

The principle of operation heretofore described applies also to the modified form of my impeller shown in Figs. 17 to 20 inclusive. In this form a reversing endless cam path 34 is cut into the periphery of an impeller shaft 36. The cam path 34 is in the form of a right and left hand spiral groove on the opposite sides and around the shaft, the pitch of the grooves being altered at each end of the path to blend into a continuous reversing path. A cam follower in this form includes a follower head 37 of generally elliptical cross section slidable edgewise in the cam path 34 and so confined therein as to transmit rotating and sliding force to the impeller body. A follower stem 38 extends from the follower head 37 and drivingly engages the impeller to be driven on said shaft. This follower stem 38 is journaled in a hollow bearing 39 which latter is suitably mounted on the hub 41 of the modified impeller. This form is a single hub with a pair of diametrically opposite bucket blades 42 of the same type as the bucket blades 8 heretofore described, except that the inner corner 43 of each bucket blade 42 protrudes somewhat further from the hub periphery.

The supporting mounting of the ends of the shaft, shown in Figs. 2 and 6 is such that the impact of the impeller blades striking the liquid is not transmitted to the casing 3 directly. This mounting also prevents the leaking or splashing of water from the casing. Each end of the impeller shaft 2 is journaled in a journal block 44, which latter is supported on the free end of an arcuate spring bar 46 by a clamping screw 47. The other end of the spring bar 46 is adjustably held in a sleeve bracket 48 on an outer flange

49 of the casing 3 at the bottom so that the journal blocks 44 are resiliently floating and absorb the shock and vibration of the impeller operation through said spring bars 46.

The splashing of water at said ends of the shaft 2 is prevented by a guard disk 51 fixed on the shaft 2. An outwardly extending peripheral flange 52 on the disk 51 overlaps an inwardly extended flange 53 on the casing 3 around the aperture 54 through which the end of the shaft 2 extends. The mounting of the shaft 2 and its driving mechanism are on the outside of the casing 3.

The driving mechanism 4, in the herein illustration, includes an electric motor 56 in a compartment under the casing 3 and a suitable pulley and belt transmission 57 between the motor 56 and the end of the impeller shaft 2. The motor 56 is controlled by any suitable electric current control, not herein shown.

The impeller sprayer heretofore described is shown in the herein illustrative embodiment in a dishwashing machine. The casing 3 is made to be suitable for the handling of dishes. The casing 3 has a bottom 58, sides 59, a back wall 61, a front wall 62, and a domed top 63. On the front wall 62 is a door 64 for access to the interior of the casing 3. The casing 3 has therein a set of suitable dish racks. One rack 66 is parallel with and is alongside the impeller device and is shown loaded with plates 67. Another rack 68 is spaced above the first rack and is substantially parallel therewith. A stepped cup rack 69 is above the impeller. A swingable rack 71 suitably overlaps the cup rack 69 above the impeller. Around the sides 59 of the casing 3 are the outer flanges 49, on which the bearing bracket bars 46 are mounted as heretofore described. On the domed top 63 of the casing 3 are a plurality of return baffles 72.

The bottom 58 of the casing is inclined from the front wall 62 downward toward the back wall 61, and the trough 6 is formed in the bottom 58 at the back wall 61. The impeller 4 is mounted above the trough 6 as heretofore described. A control baffle 73 extends along the bottom 58 between the first rack 66 and the impeller 4 and separates the trough 6 from the space above the remaining surface of said bottom 58. Most of the water from the dishes falls back to the higher part of the bottom 58 and is held there by the control baffle 73. Ports or openings 74 at the lower portion of the control baffle 73 allow a limited amount of return flow to the trough 6 so as to maintain a substantially constant liquid level in said trough 6.

In about the middle of said inclined bottom 58 and adjacent the upper side of the baffle 73 is formed an indented sump 76. In the bottom of the sump 76 is circular hole 77 in a circular rest flange 78. A drain fitting 79 extends through the hole 77 and has its support flange 81 resting on said rest flange 78. A drain passage 82 extends through the drain fitting 79 to a drain pipe 83. The intake end of the drain passage 82 is formed into a frusto-conical seat 84 into which fits a hollow cone plug 86. The apex of the cone plug 86 has a hole through it into which is fixed a waste tube 87, the top of which extends above the level of the control ports 74 of the control baffle 73, so that the tube 87 operates as an overflow drainage. Across the tube 87 and near its top extends a pin 88 which rests on a vertical link 89, which latter extends through the lower end of the tube 87 and out through a packed

hole 91 in the bottom of the drain fitting 79 and connects to lift lever 92. This lift lever 92 is fulcrumed below the bottom of the casing 3, so that it can be manually lifted for pushing up the link 89 and thus raising the tube 87 and the plug 86 from the drain seat 84, and allowing drainage through the drain passage 82. When the drain is closed overflow can drain through the top of the tube 87 into said passage 82. Waste particles that are heavier than the liquid used in the machine, sink into the sump 76 and ultimately collect in the hollow top of the cone plug 86 around the base of the tube 87. Grease, or lighter waste particles, can flow out through the waste tube 87, especially because the surface of the liquid at the sump 76 is relatively tranquil and protected from impeller disturbance by the baffle 73. The tube 87 and the cone plug 86 can be lifted off the link 89 and out of the seat 84 for cleaning out the particles collected in the top of the cone plug 86.

For rinsing the dishes, I provide a rinse tube 93 with rinse orifices 94 through the side thereof. One end of the rinse tube 93 is slidably supported on an intake conduit 96 extended through one side of the casing 3. The other end of the rinse tube 93 slidably extends through a suitable packing to the outside of the other side of the casing 3 and has a knob 97 on its end, whereby the tube 93 can be reciprocated axially and turned to direct the rinsing streams in various directions upon the dishes in the machine. The intake conduit 96 is suitably connected to rinsing liquid supply. The axial movement of the rinsing tube allows the use of lesser number of holes with greater quantity flowing from each hole. The rotation of the tube permits better rinsing action, and also facilitates the cleaning of the bottom of the case 3 after draining.

40 In operation, water or liquid is introduced into the bottom of the casing 3 in any suitable manner and is regulated to a suitable added flow during operation. The drain overflow and baffle maintain the liquid in the trough below the impeller 45 at a suitable level for the impeller blade action as heretofore described. The dishes are placed on the racks and the motor is turned on. After the washing is performed, the motor is turned off, and the rinsing water is turned on, and the rinsing tube is manipulated in the manner heretofore 50 described. The reciprocating and centrifugal action of the impeller performs a thorough and efficient washing operation, and the entire machine operates positively, with minimum vibration, and without complicated adjustments.

I claim:

1. A sprayer impeller device, comprising a rotating shaft, a frame on the shaft rotated by said shaft, coacting elements on the shaft and 60 on the frame to impart axial movement to the frame on the shaft successively in opposite directions, and bucket blades rotating and moving with the frame for spraying liquid, and means to maintain a body of liquid beneath said frame and in the path of said bucket blades.

2. A sprayer impeller device, comprising a rotating shaft, a frame on the shaft rotated by said shaft, coacting elements on the shaft and on the frame to impart axial movement to the frame on the shaft successively in opposite directions, and bucket blades rotating and moving with the frame for spraying liquid, and means to maintain a body of liquid beneath said frame and in the path of said bucket blades, each bucket blade including a bucket portion protrud- 70 75

ing generally tangentially from the periphery of said frame, and being open at its tip facing in the direction of rotation of said frame, a channel on the bottom of the bucket formed at a predetermined angle with respect to the axis of the frame, said bucket emptying into said channel at a point spaced from said tip to discharge water from said channel generally radially and partly axially and by action of centrifugal force.

3. A sprayer impeller device, comprising a rotating shaft, a frame on the shaft rotated by said shaft, coacting elements on the shaft and on the frame to impart axial movement to the frame on the shaft successively in opposite directions, and bucket blades rotating and moving with the frame for spraying liquid, and means to maintain a body of liquid beneath said frame and in the path of said bucket blades, each bucket blade including a bucket portion protruding generally tangentially from the periphery of said frame, and being open at its tip facing in the direction of rotation of said frame, a channel on the bottom of the bucket formed at predetermined angle with respect to the axis of the frame, said bucket emptying into said channel at a point spaced from said tip to discharge water from said channel generally radially and partly axially and by action of centrifugal force, the channels of the blades being at different angles with respect to said axis of rotation.

4. A sprayer impeller device, comprising a rotating shaft, a frame on the shaft rotated by said shaft, coacting elements on the shaft and on the frame to impart axial movement to the frame on the shaft successively in opposite direction, and bucket blades rotating and moving with the frame for spraying liquid, said coacting elements including an endless reversing cam path and a cam follower engaging said cam path, and means to maintain a body of liquid beneath said frame and in the path of said bucket blades.

5. A sprayer impeller device, comprising a rotating shaft, a frame on the shaft rotated by said shaft, coacting elements on the shaft and on the frame to impart axial movement to the frame on the shaft successively in opposite directions, and bucket blades rotating and moving with the frame for spraying liquid, said coacting elements including an endless reversing cam path cylindrical on and concentric with said frame, and a cam follower fixedly extended from the said shaft into engagement with said cam path, and means to maintain a body of liquid beneath said frame and in the path of said bucket blades.

6. A sprayer impeller device, comprising a rotating shaft, a frame on the shaft rotated by said shaft, coacting elements on the shaft and on the frame to impart axial movement to the frame on the shaft successively in opposite directions and bucket blades rotating and moving with the frame for spraying liquid, said coacting elements including an endless reversing cam path on the shaft, and a cam follower extended from said frame generally radially and into engagement with said cam path, and means to maintain a body of liquid beneath said frame and in the path of said bucket blades.

7. A sprayer impeller device, comprising a rotating shaft, a frame on the shaft rotated by said shaft, coacting elements on the shaft and on the frame to impart axial movement to the frame on the shaft successively in opposite directions, and bucket blades rotating and moving with the frame for spraying liquid, and a vibration absorbing support for each end of said shaft in-

cluding a bearing block and a generally spiral spring arm support connected to said bearing block, and means to maintain a body of liquid beneath said frame and in the path of said bucket blades.

8. A sprayer blade for rotating sprayer devices of the character described, comprising a bucket having an open end generally radial with respect to the axis of rotation of said rotating device and protruding outwardly from said device, a wall inclined from the leading edge of said opening and toward said device, a closed heel formed at the trailing end of said bucket wall, a channel extended from said heel toward said leading edge on the outside of said wall and diverging from said wall outwardly, the trailing portion of said channel being open into said bucket, and the leading end of said channel being open to eject by action of centrifugal force liquid picked up by said leading edge and dropped into said channel.

9. A sprayer blade for rotating sprayer devices of the character described, comprising a bucket having an open end generally radial with respect to the axis of rotation of said rotating device and protruding outwardly from said device, a wall inclined from the leading edge of said opening and toward said device, a closed heel formed at the trailing end of said bucket wall, a channel extended from said heel toward said leading edge on the outside of said wall and diverging from said wall outwardly, the trailing portion of said channel being open into said bucket, and the leading end of said channel being open to eject by action of centrifugal force liquid picked up by said leading edge and dropped into said channel, said channel being at a transverse angle with respect to said bucket wall.

10. A sprayer blade for rotating sprayer devices of the character described, comprising a bucket having an open end generally radial with respect to the axis of rotation of said rotating device and protruding outwardly from said device, a wall inclined from the leading edge of said opening and toward said device, a closed heel formed at the trailing end of said bucket wall, a channel extended from said heel toward said leading edge on the outside of said wall and diverging from said wall outwardly, the trailing portion of said channel being open into said bucket, and the leading end of said channel being open to eject by action of centrifugal force liquid picked up by said leading edge and dropped into said channel, and the leading end of said wall being curved inwardly toward said leading edge to form a pickup trough.

11. A spraying impeller comprising a rotating frame, and a plurality of bucket blades on said frame, each bucket blade including a bucket having an open end generally radial with respect to the axis of rotation of said rotating device and protruding outwardly from said device, a wall inclined from the leading edge of said opening and toward said device, a closed heel formed at the trailing end of said bucket wall, a channel extended from said heel toward said leading edge on the outside of said wall and diverging from said wall outwardly, the trailing portion of said channel being open into said bucket, and the leading end of said channel being open to eject by action of centrifugal force liquid picked up by said leading edge and dropped into said channel, said channels on the different buckets being at different transverse angles with respect to said frame.

12. A spraying impeller comprising a rotating frame, and a plurality of bucket blades on said frame, each bucket blade including a bucket having an open end generally radial with respect to the axis of rotation of said rotating frame and protruding outwardly from said frame, a wall inclined from the leading edge of said opening and toward said frame, a closed heel formed at the trailing end of said bucket wall, a channel extended from said heel toward said leading edge on the outside of said wall and diverging from said wall outwardly, the trailing portion of said channel being open into said bucket, and the outer end of said channel being open to eject by action of centrifugal force liquid picked up by said leading edge and dropped into said channel, said channels on the different buckets being at different transverse angles with respect to said frame, and means to reciprocate said rotating frame with said bucket blades axially with respect to the axis of rotation of the frame. 20

13. In a washing machine of the character described, a casing, racks in the casing for holding articles to be washed, a rotating sprayer in said casing comprising a rotating shaft supported on a generally horizontal axis in said casing, a spraying frame on said shaft, generally radial spraying bucket blades on said frame, and a drive connection device between said frame and said shaft for rotating said frame and imparting horizontal reciprocation to said frame along said rotating shaft.

14. In a washing machine of the character described, a casing, racks in the casing for holding articles to be washed, a rotating sprayer in said casing comprising a rotating shaft supported on a generally horizontal axis in said casing, a spraying frame on said shaft, generally radial spraying bucket blades on said frame, and a drive connection device between said frame and said shaft for rotating said frame and imparting horizontal reciprocation to said frame along said rotating shaft, a trough formed in said casing along said frame and shaft, a liquid collecting element in said casing and a device determining liquid flow from said element to said trough so as to maintain a constant liquid level in said trough in the path of said bucket blades. 45

15. In a washing machine of the character de-

scribed, a casing, racks in the casing for holding articles to be washed, a rotating sprayer in said casing comprising a rotating shaft supported on a generally horizontal axis in said casing, a spraying frame on said shaft, generally radial spraying bucket blades on said frame, and a drive connection device between said frame and said shaft for rotating said frame and imparting horizontal reciprocation to said frame along said rotating shaft, a trough formed in said casing along said frame and shaft, a sump formed in said casing adjacent said trough and being separated from the latter, a baffle projecting above the liquid level in said sump and trough, said baffle having ports for allowing return flow of liquid from said sump into said trough for maintaining liquid level in said trough in the path of said bucket blades.
